UNITED STATES PATENT OFFICE.

JOHN E. WRINN, OF PROVIDENCE, RHODE ISLAND, ASSIGNOR TO CHARLES F. IRONS AND CHARLES A. RUSSELL, OF PROVIDENCE, RHODE ISLAND; (COPARTNERS AS IRONS & RUSSELL.)

DESIGN FOR A BADGE.

SPECIFICATION forming part of Design No. 35,197, dated October 22, 1901.

Application filed May 25, 1901. Serial No. 61,977. Term of patent 7 years.

To all whom it may concern:

Be it known that I, JOHN E. WRINN, a citizen of the United States, residing at Providence, in the county of Providence, in the State of Rhode Island, have invented and produced a new and original Design for Badges, of which the following is a specification; reference being had to the accompanying drawings, forming a part thereof.

10 Figure 1 is a plan view of my said design for badges. Fig. 2 is a side elevation of the same.

The principal and material feature of my design is a plate having a margin or border, 15 which comprises four arc-shaped scrolls arranged on the four quarters of said plate, each of said scrolls terminating at each of its ends in an inwardly-directed circle whose diameter exceeds the breadth of said scroll and 20 between which scrolls are sections, each having a concave curved base and an obtuse angular exterior, as seen in plan and illustrated in Fig. 1. Centrally displayed on said plate is a shield having a parallel line close to its 25 edge all around the same. Centrally displayed on said shield are represented two shovels whose handles cross each other diagonally, and a slicing-iron is represented as extending centrally and longitudinally between 30 said shovels, these implements being

emblematic of the work of a fireman of locomotive-engines. Around this plate is a border of open scrollwork, consisting, as shown, of six spears arranged radially and separated sixty degrees apart and having spear-heads 35 at their outer ends, respectively, and each spear-handle is supported on both sides by volutes touching the same with their outer curved ends and having their inner ends respectively touching the inner end of the contiguous volute of the next adjacent spear-handle, the essential feature of my design being the said plate having the margin or border as described and having centrally displayed thereon the shield with the crossed 40 shovels and slicing-iron, as specified and shown in the drawings.

Having thus described my invention, what I claim as new, and desire to secure by Letters Patent, is—

The design for a badge, as herein shown and described.

In testimony whereof I have signed my name to this specification in the presence of two subscribing witnesses.

JOHN E. WRINN.
